CLARENCE A. LINDSAY, OF EAST ORANGE, NEW JERSEY, ASSIGNOR TO THE CHAPMAN TRUCK COMPANY, OF HOLYOKE, MASSACHUSETTS, A FIRM.

TRUCK.

1,148,599.

Specification of Letters Patent.

Patented Aug. 3, 1915.

Application filed June 29, 1914. Serial No. 847,797.

To all whom it may concern:

Be it known that I, CLARENCE A. LINDSAY, a citizen of the United States of America, and resident of East Orange, in the county 5 of Essex and State of New Jersey, have invented certain new and useful Improvements in Trucks, of which the following is a full, clear, and exact description.

This invention relates to trucks that are 10 employed to carry goods short distances as around a warehouse or station, and are usually drawn by means of a handle projecting at the front of the truck, and to the particular form of truck that is provided with a 15 supplemental frame that can be elevated by the swinging downward of the draft handle from a substantially upright position.

The object of the invention is to provide 20 a foot lever attachment for the draft handle of the truck of the character above indicated which may be engaged by the foot of a person operating the truck in order to obtain leverage and power, additional to that imparted by the arms to swing the handle 25 downward whereby the supplemental frame of the truck, with the load thereon, is elevated. And a further object is to render the foot attachment foldable relatively to the draft handle and to provide spring 30 means to secure the retention thereof when in its folded position closely alongside the draft handle.

In the accompanying drawings illustrating 35 one embodiment of my invention,—Figure 1 shows in side elevation a truck of this character with the lever in closed position. Fig. 2 is a similar view with the supplemental frame in lowered position and the draft handle upright, with the foot lever 40 swung down to position for operation. Fig. 3 is a front elevation of the lever showing a portion of the draft handle, and Fig. 4 is a side elevation of the same parts, showing in broken lines the lever in the lowered position. Fig. 5 shows a side elevation of the 45 foot lever reduced.

In Figs. 1 and 2 of the drawing, I represent a truck of the character that can be operated to elevate the load by the swinging of 50 the draft handle, which truck is indicated as having a main frame member 6 connecting the front and rear wheels 7 and 8, and a lifting frame 9 supported by links 10 and 11, and which frame can be elevated from 55 the lowered position in which it is shown

in Fig. 2 to the elevated position of Fig. 1 by the operation of swinging the draft handle 12 from the upright position of Fig. 2, to an inclined position as indicated in Fig. 1.

I provide a foot lever 14 that is suitably hinged to the handle 12 near its lower end, and the lever is provided with a lateral extension 15 at its free end to engage the foot 60 of the user of the truck.

I connect the lever 14 with the handle member by means of a coil spring 16, so that the lever can be normally retained adjacent the draft handle by the tension of this spring, but when the lever is swung to a 70 transverse position, or one perpendicular to the handle, the spring will move to or beyond a position of dead center.

In the form shown, I provide a socket member 17 adapted to slide on the handle 75 12 and be locked in position by a clamp bolt 18.

The handle 14 is pivoted to the socket member at 19, and when swung to a position perpendicular to the handle 12 will engage 80 an abutment 20 to limit its movement in this direction.

The coil spring 15 is attached to a stud 21 on the lever 14 by one end, while its other end is secured to a pin 22 on the socket member, whereby when the lever is swung down from the position adjacent the handle as shown in Figs. 1 and 3, to the transverse position indicated in Fig. 2, and in broken lines in Fig. 4, the spring will be tensioned 90 and will pass to or beyond a dead center, that is the axis of the spring will move to or beyond the axis of the pin 19 of the lever; whereby the tension of the spring cannot now act to move the lever from this transverse position; but as soon as the lever is given a small advance movement, and the spring passes beyond the pin 19, it will serve to swing the lever up adjacent the handle 12, and retain it in this position.

To further assist in retaining the lever in the transverse position, I employ a lug 23 on the socket member, that is engaged by the spring in the transverse position of the lever to further tension the spring and the 105 friction between the lug and the spring will assist in retaining the lever in this position.

In the use of the device, when the draft handle of the truck is brought to the upright position as indicated in Fig. 2, the 110

operator will grasp the handle by his hand and by placing the foot on the arm or extension 15, the lever can be swung down to the transverse position as indicated in Fig. 2; and then the foot of the operator is placed on the arm 15 of the lever, and the weight of the operator can be thrown on this lever, that as it projects some distance in front of the axle 7 on or near which the lever 12 swings, much greater power is provided for swinging the handle 12 down to the inclined position to elevate the movable frame 9.

It will be seen that the lug 23 is inclined 15 or in the form of a wedge as set forth in Fig. 3.

I claim:—

1. A truck provided with a vertically movable load supporting portion, and a 20 draft handle adapted to swing in a vertical plane and coöperative with the load supporting portion to elevate and lower the same, and said handle having a forwardly projecting foot lever at a lower portion 25 thereof.

2. In a truck provided with an arrangement for elevating a load supporting portion and which is actuated by the swinging in a vertical plane of a draft handle, a foot 30 lever having a hinge connection with the handle, and a spring arranged to retain the lever when moved from a position angular to the handle to a position adjacent and alongside the handle in such latter position.

3. In a truck provided with an arrangement for elevating a load supporting portion and which is actuated by the swinging in a vertical plane of the draft handle, a foot lever comprising an arm hinged to the 40 handle having a horizontal extension at the free end, means for supporting the arm when brought perpendicular to the handle below the same, and a coil spring arranged to swing the lever when advanced from such 45 position and retain it adjacent the handle.

4. In a truck provided with an arrangement for elevating a load supporting portion and which is actuated by the swinging in a vertical plane of the draft handle, a 50 foot lever comprising an arm hinged to the handle having a horizontal extension at the free end, means for supporting the arm when brought perpendicular to the handle below the same, and a coil spring arranged 55 to swing the lever when advanced from such

position and retain it adjacent the handle, said spring being connected between the lever and the handle to be on a dead center when the lever is in the lowered position, and a friction device connected with the 60 handle engaging the spring in said position.

5. In a device of the character set forth, the combination of a socket member adapted to be attached to a truck handle and provided with a hinge portion, a lever pivoted 65 to swing in the hinged portion from a position adjacent the handle to extend perpendicular thereto and be retained by an abutment in such position against the further movement, and means for retaining the lever 70 adjacent the handle and also in said perpendicular position.

6. A device of the character described comprising a socket portion adapted to be secured to a truck and having a hinge portion, a lever pivoted in the hinge portion and having a lateral extension at the free end to be swung from a position adjacent the handle to a position perpendicular thereto, an abutment engaging the lever in 80 the latter position to prevent further movement, a coil spring connected between the socket and the lever that is on dead center in the said perpendicular position and which serves to swing the lever when advanced 85 from said position and retain it adjacent the lever.

7. A device of the character described comprising a socket portion adapted to be secured to a truck and having a hinge portion, 90 a lever pivoted in the hinge portion and having a lateral extension at the free end to be swung from a position adjacent the handle to a position perpendicular thereto, an abutment engaging the lever in the 95 latter position to prevent further movement, a coil spring connected between the socket and the lever that is on a dead center in the said perpendicular position and which serves to swing the lever when advanced 100 from said position and retain it adjacent the lever, and a portion on the socket arranged to engage the spring in the said perpendicular position of the lever.

Signed by me at Springfield, Mass., in 105 presence of two subscribing witnesses.

CLARENCE A. LINDSAY.
